UNITED STATES PATENT OFFICE.

JOSEPH LAZERUS, OF PHILADELPHIA, PENNSYLVANIA.

DESIGN FOR A SWIVEL CONFECTION RACK.

61,168.

Specification for Design.

Patented July 4, 1922.

Application filed July 2, 1921. Serial No. 482,221. Term of patent 7 years.

To all whom it may concern:

Be it known that I, JOSEPH LAZERUS, a citizen of the United States, residing at Philadelphia, in the county of Philadelphia and State of Pennsylvania, have invented a new, original, and ornamental Design for a Swivel Confection Rack, of which the following is a specification, reference being had

to the accompanying drawing, forming part thereof.

The figure is a perspective view of a swivel confection rack embodying my design.

I claim:

The ornamental design for a swivel confection rack, as shown.

JOSEPH LAZERUS.
